UNITED STATES PATENT OFFICE.

ALBERT M. EDWARDS, JR., OF LAWRENCE, MASSACHUSETTS.

BOTTLE-STOPPER.

No. 854,201.

Specification of Letters Patent.

Patented May 21, 1907.

Application filed March 13, 1907. Serial No. 362,089.

To all whom it may concern:

Be it known that I, ALBERT M. EDWARDS, Jr., of Lawrence, in the county of Essex and State of Massachusetts, have invented certain new and useful Improvements in Bottle-Stoppers, of which the following is a specification.

This invention has relation to bottle stoppers of the type in which a metallic cap is attached to the mouth of the bottle to seal the same.

The commercial form of bottle stoppers consists of a metallic cap having a circular rim or flange which is crimped or fluted, a layer of cork, and a layer of paraffin paper interposed between the layer of cork and the cap. This cap is secured to the mouth of the bottle by bending in the crimped portions of the flange or rim so as to embrace a bead surrounding the neck of the bottle. Owing to the difficulty of obtaining cork which is unperforated, it frequently happens that caps are supplied in large numbers with corks that are defective in that they have small holes or cracks which permit the leakage of the contents of the bottle, or through which the liquid or gas contained in the bottle may pass, so as to oxidize or destroy the metallic cap and impair the quality of the contents of the bottle. Again, another difficulty has been found with the use of these caps in which the contents of the bottle may come in contact with the cork, to wit,—that after a while the contents of the bottle contain numerous small pieces or specks of cork and dirt deposited from the cork layer, and, especially where the bottle contains pure water, the water tastes "corky" and its commercial value is destroyed.

In one form of cap stopper in which a locking ring is employed in connection with the cap, it has been proposed to introduce between the layer of cork and the mouth of the bottle, a thin layer of tenacious or ductile metal, but this form of stopper has not been commercially successful, probably owing to the difficulty of securing the layer of ductile metal in the cap and of fastening the cap on the bottle after the layer has been secured in it. I have found by experience that by employing a sheet of ductile metal such as chemically pure block tin, aluminium or alloys of

tin, in conjunction with a layer of elastic material such as cork, and a crimped cap, the bottle may be effectively sealed and the contents thereof remain unimpaired for a long time even though the cork is defective. After numerous experiments, I have devised means for securing the layer of ductile metal in place in the cap by forming it with a bent rim or flange, and placing the disk so formed in the cap, with the flange or rim inserted between the layer of cork and the cylindrical wall of the cap. When the parts are assembled, the lateral pressure of the cork against the rim or flange of the disk of ductile metal serves to hold it in place so that the stoppers may be placed in the machines and also shipped in quantities, all without danger of the dislocation of the disks. I have further found that, after the cap is secured to the bottle, the flange is caused to press even more tightly against the surrounding cylindrical wall of the cap so as to securely hold it against lateral movement and prevent its dislocation when the cap is removed.

Referring to the accompanying drawings,—Figure 1 represents a bottle stopper embodying the invention. Fig. 2 represents a section through the same. Fig. 3 represents a view of the ductile disk detached. Fig. 4 represents a section through the bottle with the cap secured thereon.

Referring to said drawings, *a* indicates the cap which is formed with a substantially cylindrical flange *a'*, and a crimped rim *a''*. This cap is made, as usual, of thin sheet iron coated with tin. *b* indicates a layer of compressible elastic material, preferably cork, which fits within the cavity in the cap.

c indicates the usual layer of paraffin paper.

d represents a disk of thin ductile metal such as block tin, aluminium or tin alloys. This disk is initially formed with a flanged rim *d'*, and, as previously stated, the disk is forced into the cap so that the rim *d'* fits between the periphery of the cork layer and the cylindrical wall of the rim. When the disk is placed as described, it is held against removal by its frictional engagement with the cylindrical wall of the cap, and by the lateral pressure of the cork.

Having thus illustrated the nature of the

said invention and described a way of constructing and using the same, although without attempting to set forth all of the forms in which it may be made or all of the modes of its use, I declare that what I claim is:—

A bottle stopper comprising a metallic cap having a cylindrical wall, a layer of compressible material in the cap, and a disk of ductile metal exterior to said last-mentioned

layer and having at its edge an inturned or flange, substantially as set forth.

In testimony whereof I have affixed my signature, in presence of two witnesses.

ALBERT M. EDWARDS, JR.
